ERNST NÖLKE, OF BERLIN HALENSEE, GERMANY, ASSIGNOR TO SIEMENS & HALSKE AKTIENGESELLSCHAFT, OF WERNERWERK SIEMENSSTADT, NEAR BERLIN, GERMANY

CHEEK MICROPHONE

Application filed September 23, 1929, Serial No. 394,433, and in Germany January 22, 1929.

It is known to effect the transformation of acoustic oscillations of the human voice into electrical current oscillations by means of a microphone, which is pressed to the throat near the larynx. These laryngaphones are chiefly used wherever, for example, in engine rooms, aeroplane pilot's seat and the like, the extraneous noises are so loud that they drown the human voice. But the laryngaphone has the drawback that it much molests the user, furthermore clearness is incomplete because gutteral sounds can be clearly understood only by those much practiced therein.

According to the invention the acoustic oscillations of the voice are so received that a sound receiving device (microphone) is applied to the cheek. Tests have demonstrated that this arrangement of the microphone much improves the transmission of sound. Furthermore it is easy to fix the cheek microphone for example to the head covering, and when it is worn for some time, it molests the wearer less than a laryngaphone, which usually lies close to the throat by means of a band surrounding the throat. In addition it is easy to arrange that it only lies close to the cheek when conversation is taking place, but at other times only slightly touches the cheek or when not in use is swung away from the cheek in any manner.

Preferably the cheek microphone is fixed to an arm or the like, which is fixed to the head covering by means of a spring and preferably is adjustably fitted. Especially when used with divers' or airmen's helmets, uniform caps or the like is it advantageous to provide a bar, to which the cheek microphone can be fitted by means of a spring arm, which is displaceable. In order that the bars may conform better to the shape of the head, they can likewise be made up of springs. They can also be fitted to the holding device of the head receiver or can be so arranged that they at the same time serve as supports for the head receiver.

The drawings show examples of the construction according to the invention.

Fig. 1 shows a cheek microphone, which

is fitted to the supporting frame of a head receiver for caps, helmets or the like.

Fig. 2 shows a similar construction, wherein however there is a front view of the supporting frame of a head receiver provided with a special bar for the cheek microphone.

Fig. 3 shows the same device in section along line A—B.

Fig. 4 shows another form of the same type of construction. Figs. 5 and 6 show in elevation and plan views an example of the cheek microphone having a device for swinging it away when not in use.

Parts functioning in similar manner have the same designation in all the figures.

In the arrangement according to Fig. 1 two parallel spring bars 1, 1', which preferably comprise wire or the like wound spirally, are combined by the connecting strips 2, 2' to form a frame. This frame is fixed to head coverings, such as helmets, caps or the like at the side at the height of the ear, this being done for example by sewing the slot 8 thereto. The head receiver is provided with rings to slide along the bars 1, 1', so that it can be brought into a convenient position. A sliding ring 14, which is provided at the supporting arm 5 of the microphone 4, is connected to the sliding device of the head receiver by means of the spiral spring 7. The microphone 4 is so arranged that it lies on the cheek when the head covering has been put on.

When it is desirable that the head receiver and microphone be separately brought into a suitable position, a construction of the kind shown in the Figs. 2 and 3 can be adopted. The microphone 4 is fixed to the leaf spring 5. This terminates in a ring, which enables it to slide along the bar 9. Preferably the bar 9 is fixed to the lower cross piece 2' of the frame supporting the receiver. When not in use, the spring supporting arm 5 of the microphone 4 assumes the relaxed position shown dotted in the Fig. 3. Only one putting on the head covering, does the supporting arm 5 reach its pensioned position, so that the microphone then lies against the cheek with a slight pressure.

As shown in Fig. 4, the sliding bar 9 of the

microphone can also be fitted at the side of the bars 1, 1' of the head receiver. In this example the supporting arm 5 of the microphone 4 is connected to the sliding ring 14 by means of a hinge 15. The sliding ring 14 has a spring 7, which presses the arm 5 and the microphone 4 against the cheek.

Finally the Figs. 5 and 6 show in side elevation and plan a tilting device for the microphone. Its purpose is to lift the microphone off the cheek when not in use. By means of the sliding ring 14, the arm 5' can be pushed along the bar 9 which is only partially shown. The microphone arm 5 is hinged onto the arm 5'. A tension spring 10 is tensioned between the extension pieces 12 and 13 of the two arms. This spring holds the microphone 4 either in the position shown by full or dotted lines. In the former position the microphone is pressed against the cheek with a light spring pressure, while in the latter position it does not touch the cheek. This arrangement has the advantage that it enables the microphone to be placed against the cheek only for the duration of a conversation, so that during the rest of the time it in no way hinders the user of the cheek microphone.

What is claimed is:

30. 1. In combination with a support for connection with a head piece, a telephone receiver adjustably connected to said support, so that the receiver may be brought into close proximity with the ear of the wearer of the head piece, a telephone transmitter also adjustably connected to said support so that the transmitter may be brought against the cheek of the wearer, and auxiliary means for removing the transmitter away from the cheek while not in use.
35. 2. In combination, a support for connection with a head-piece, a telephone receiver adjustably secured to said support, a telephone transmitter also adjustably secured to said support, and means for holding said transmitter under tension against the cheek of the wearer of the head piece.
40. 3. In combination, a plurality of vertical members provided with cross members to form a unit and for use in holding said unit to a head piece, a receiver secured to and vertically movable on certain of said vertical members, an arm secured to one of said members and vertically movable thereon, and a spring for selectively maintaining the transmitter into or out of talking position.
45. 4. In an arrangement for communication between aviators or the like, a transmitter, and a framework upon which said transmitter is adjustably and flexibly mounted to press lightly against the cheek of the user when in talking position.
50. 5. In an arrangement for communication between aviators or the like, a pair of vertically-disposed bars for attachment to a head-

piece, a receiver slidably mounted on said bars to enable the receiver to be properly positioned with respect to the user's ear, and a transmitter slidably secured to one of said bars and tensioned to rest lightly against the cheek of the user.

In witness whereof, I hereunto subscribe my name this 29th day of August, A. D. 1929.

ERNST NÖLKE.
